UNITED STATES PATENT OFFICE.

WINFIELD E. HINSDALE, OF NEW YORK, N. Y.

URINAL-STALL.

974,145.

Specification of Letters Patent. Patented Nov. 1, 1910.

Application filed November 10, 1908. Serial No. 461,985.

To all whom it may concern:

Be it known that I, WINFIELD E. HINSDALE, a citizen of the United States, and resident of New York city, borough of Manhattan, county and State of New York, have made a new and useful Invention in Urinal-Stalls, of which the following is a specification.

My invention is directed particularly to improvements in urinal stalls of that type in which the individual stall proper embraces a body, a top and a receptor usually formed of glazed earthenware and in one integral piece, and it has for its objects, first, to provide a urinal stall constructed of a minimum number of pieces in which two end-plates shall completely cover the sides of the stall and be so disposed with relation thereto as to avoid, so far as possible, unsightly joints. Second, to provide a battery of two or more such stalls in which the joints between the dividing partition or partitions and the front edges and tops of the stalls shall afford a more sightly appearance than has been possible with batteries of stalls of this nature heretofore, and also to overcome as far as possible the evil effects due to the sagging of adjoining stalls upon the joints, as heretofore constructed. Third, to construct a battery of such stalls of a minimum number of parts. Fourth, to construct a battery of such stalls in which all of the joints between the individual parts of the stalls, the partitions, the end-surfaces or walls and the tops shall be so arranged as to present the least possible evidence thereof, either in the event of a sagging of the stalls from or toward each other; or from any inequalities due to sagging of the floor or any part of the battery whatever.

Prior to my improvements a number of types of urinal stalls had been devised. Among others, individual stalls constructed of glazed earthenware, the body of which was semi-circular with an open front, said body terminating at its base with a funnel-shaped construction, constituting what is termed the receptor in which is located an outlet for the waste. The top of this urinal body was left open and covered by separate or individual pieces of glazed earthenware. Urinal stalls of this type were placed side by side and covered on their front edges with pilaster pieces ornamenteally molded and reaching from the floor to the top edge of each urinal body under the be-

fore-mentioned top-pieces. The ends of such batteries were constructed of separate or individual blocks of flat form or shape extending back to the wall, the front edge 60 thereof being covered by molded pilasters. A battery of such urinal stalls embraced twelve pieces in all for a two-part combination, as follows:—two bodies; two ends; two end top pieces; one center top piece; three pilasters, and two top joint covers, and all showing at the intersecting points more or less widely separated joints which were filled with plaster. This plaster not being provided with glaze soon became 70 soiled and thus damaged the appearance of the urinal stall, in addition to being unsanitary on account of the absorptive qualities of the plaster. A further type of such batteries has also been devised, in which 75 the stall is in the nature of an earthenware box with an open front, its body being semi-circular in form and its bottom extending forward so as to make the drip-pan for the receptor, the top of which is designed to be 80 level with the floor and in which the floor drip could drain, but such an arrangement afforded no guarantee against leakage between the outer edge of the receptor and the floor. Stalls of this type were set up 85 with a partition piece between them of the same material. Sometimes this partition piece was extended forward beyond the base of the receptor to a considerable distance, thus affording more extended partitions between adjacent stalls and undercut from 90 knee-high to the floor. Again they were only extended forward a sufficient distance to give an ornamental effect, but in either case any variation of any number of such 95 stalls from a true parallelogram as to its sides made it necessary to fill the spaces with plaster, thereby offering the same objections urged to the first described battery of individual stalls. In a two stall battery of 100 this type it will, therefore, be apparent that five pieces instead of twelve are necessary; that is to say, two integral body pieces with three partitions. Furthermore, with either 105 of the types above described it has been found impossible to form between the outer top edge of the receptor and the floor, after such urinal stalls have been placed in position against the wall or back to back when thus disposed, an absolutely water-tight 110 joint.

It was with a view of overcoming the sev-

eral objections to such structural urinal stalls and batteries thereof that the present improvements were devised and which improvements may be fully understood by referring to the accompanying drawings, in which,

Figure 1 is a perspective view of a battery of three of my improved urinal stalls, said view illustrating also the usual flushing devices and the floor into which the stalls extend. Fig. 2 is a front elevational view of one of my improved stalls, illustrating the floor at the base thereof in section. Fig. 3 is a sectional view taken through Fig. 2 on the line C—C and as seen looking therat from left to right in the direction of the arrows. Fig. 4 is a side elevational view of one of the intermediate partitions used in a battery of my novel urinal stalls. Fig. 5 is a transverse sectional view taken through Fig. 1 on a plane indicated by the line and letters A—A and as seen looking therat from the top toward the bottom of the drawings in the direction of the arrows; and Fig. 6 is a similar view taken through Fig. 1 upon a plane indicated by the line and letters B—B and as seen looking from the top toward the bottom of the drawings; Fig. 7 is a sectional view taken through Fig. 4 on the lines D—D and as seen looking therat from left to right in the direction of the arrows. Fig. 8 is a similar view taken through one of the end-plates or partitions as seen on the right and left of Fig. 1.

Referring now to the drawings in detail in which all letters of reference and numerals represent like parts wherever used, F represents the floor and W the wall of a room in which is located a battery of my novel urinal stalls, said stalls being assembled upon the floor with the backs thereof against the wall, as clearly indicated in Figs. 1, 5 and 6.

1 represents the body of an individual stall and 2 the receptor therefor having the usual formation or shape and extending downward below the bottom of the stall wherein is provided the usual outlet, 3 representing the top of the stall and 4 a drip-lip with its top edge at the floor level.

5 constitutes an essential feature of my invention, in that it embraces a ledge or extension on the outer or front face of the receptor and beyond the drip-lip 4, the upper surface of which ledge is preferably roughened in such manner as to enable the builder in putting the stall in place to effect a water-tight joint with cement, concrete, or any of the well known flooring substances between the stall and the floor proper, as will be fully apparent on inspection of Fig. 3, so that there will always be a drainage from the floor surface by way of the glazed drip-lip 4 into the receptor and without any possibility of surface leak-

age between the urinal stall and the joint connecting it with the floor.

It will be noticed that the entire stall embracing the body 1, receptor 2, top 3, drip-lip 4 and ledge or extension 5 are cast or formed preferably of glazed earthenware in one integral piece, as clearly indicated in Figs. 2 and 3.

6 represents one of the intermediate partitions designed for use where two or more stalls are to be assembled in battery form, said partitions being molded or cast with the usual front separating part 8 extending from knee height up to the top of the stall, and additionally with two laterally extending ledges 7, 7, designed to fit accurately over the front edges and top surfaces of adjoining stalls where two or more such stalls constitute a single battery. The outer or end plates or partitions 6 are provided each with a like laterally extending ledge 7 on one edge face only. The several parts are assembled in the manner clearly illustrated in Figs. 1, 5 and 6 and the close fitting joints are filled with the necessary cement to effect the best operative results, so that it will be apparent that I am enabled to produce a battery of urinal stalls in which there is a minimum number of parts, there being required only three such parts for a single stall, and also in which the joints are of such a nature as to afford the best possible effect with the least possible damage in the event of any sagging of the parts. It will also be apparent that, as before stated, in view of the integral nature of all of the parts of an individual stall and by reason of the extension 5 I am enabled to provide a stall either for individual use or for use in a battery of the same in which absolutely water-tight effects may be had as between the drip-lip of each stall and the floor upon which the battery is assembled, thus providing a stall having the best possible sanitary effects.

Having thus described my invention what I claim and desire to secure by Letters Patent of the United States is—

1. A urinal stall embracing a body, a top, and a receptor in one integral piece and two end plates each constructed of a single piece of material and having lateral top and side ledges adapted when in place to extend over the top, the side faces and front edges of the stall, substantially as described.

2. A battery of urinal stalls embracing a plurality of individual stalls each having a body, a top and a receptor formed in one integral piece in combination with one or more partitions each constructed of a single piece of material and having laterally extending top and side ledges adapted to overlap the tops, the side faces and front edges of adjoining stalls, substantially as described.

3. A battery of urinal stalls embracing a plurality of individual stalls formed each of one integral piece; a plurality of partitions and two end plates, said partitions having each two laterally extending top and side ledges adapted to overlap the tops and outer edges of adjoining stalls; the end plates having each one a similar lateral ledge, said ledges being adapted to cover the outer faces of the end stalls and the outer and top edges thereof, the aforesaid partitions and end-plates being each constructed of a single piece of material, substantially as described.
- 15 4. A battery of urinal stalls embracing a plurality of individual stalls having each a body, a top, a receptor, a drip-lip and an extending ledge below the floor level of the

receptor; in combination with a plurality of partitions having each two laterally extending top and side ledges adapted to overlap the top and front edges of adjoining stalls and two end plates having each one a similar ledge adapted to inclose the outside faces of the end stalls, the aforesaid partitions and end-plates being each constructed of a single piece of material, substantially as described.

In testimony whereof I have signed my name to this specification in the presence of 30 two subscribing witnesses.

WINFIELD E. HINSDALE.
